UNITED STATES PATENT OFFICE.

AUSTIN ENOS KNESS, OF AUDUBON, IOWA.

PRUNING SAW.

Application filed January 15, 1926. Serial No. 81,449.

This invention relates to pruning saws, and has more particular reference to the mounting structure for the saw blade per se.

The primary object of the invention is to provide a pruning saw wherein the blade per se is maintained during the pruning operation in an absolutely taut manner and whereby the blade may be readily adjusted to cut at several angles, or in a circle in order that the cut may be flush with the tree, thereby really pruning it according to the best horticultural practices.

A further and important object is to provide a mount for pruning saw blade wherein in the cutting edge of the blade may be moved at various angles with respect to the mount without withdrawing the saw entirely from the tree.

With the foregoing and other objects in view as the nature of the invention will be better understood the same comprises the novel form, combination, and arrangement of parts hereinafter more fully described, shown in the accompanying drawing and claimed.

In the drawing wherein like reference characters indicate corresponding parts throughout the several views:

Figure 1 is a side elevation of a pruning saw constructed in accordance with the present invention.

Figure 2 is an enlarged fragmentary view partly in elevation and partly in cross section for more clearly disclosing the main features of the saw blade mount, showing the position of the rod when the blade is to be adjusted to any desired angle, and

Figure 3 is a detail vertical section taken substantially upon the line 3-3 of Figure 2.

Figure 4 is an enlarged fragmentary detail of the rod showing the octagonal portion being slightly larger in cross section than the threaded portion, and

Figure 5 is an enlarged fragmentary detail of the swivel connection.

Now having particular reference to the drawing, my novel invention constitutes the provision of a handle 5 of suitable length upon one end of which is secured one end of a bow 6 of hickory or other strong but flexible material.

Upon the same end of the handle 5 beneath the end of the bow 6 attached thereto is a pair of longitudinally spaced L-shaped brackets 7-7, the pendent leg of the foremost one of which is provided with a rela-

tively wide vertical slot 8 within which is slidably secured a nut-like guide block 9 provided centrally with an octagon shaped opening 10. The pendent portion of the other L-shaped bracket 7 is provided with a circular opening in registration with the center of the slot 8 in the foremost bracket 7.

Slidable through the octagon shaped opening 10 of the nut-like block 9 and the circular opening in the bracket 7 is a rod 11 of unthreaded octagon shape 12 at its inner end and circular at its outer end, said circular portion being threaded as at 13 upon which is arranged a nut 14 upon the outer side of the bracket 7. As is clearly shown in Figure 4, the octagonal portion 12 is larger in cross section than the threaded portion 13.

To the inner end of the rod 11 is secured one end of a pruning saw blade 15, the opposite end of which is swivelly connected to the forward end of the flexible bow 6 as indicated at 16 in Figures 1 and 5.

Pivoted to the handle 5 adjacent its lower end is a hand lever 17 to which is pivotally secured rearwardly of its pivotal connection with the handle a link 18, the forward end of which is pivotally connected to a bracket 19. Slidably secured to this bracket 19 at one end is a wire rod 20 that is in turn connected at its forward end to the bar 11 as at 21. This rod 20 is provided with a looped portion 22 adjacent its lower end to facilitate the turning of the same after the handle 17 has been swung upon its pivot away from the handle 5 which consequently throws the link 18 downwardly beneath the pivotal connection between said lever and the handle 5, and thus positioning the inner end of the rod 20 beneath the handle 5 in such a manner as to permit of the turning of the rod.

In actual use, the elements are positioned as shown in Figure 1. However, should it be desired to extend the cutting teeth 15' of the blade 15 to any one of the permissible positions with respect to the handle and mount, the lever 17 is swung downwardly from the handle 5 and due to the flexibility of the bow 6 the circular threaded portion of the bar 11 will pass into the octagon opening of the block 9 for positioning the circular threaded portion of the bar 11 within the octagon opening of the block 9. The rod 20 may then be turned for positioning the blade 15 at the desired angle and main-

tained at this angle by reversely swinging the lever 17 which will pull upon the rod 20 and bar 11 causing the octagon portion to pass into the octagon opening of the block 9.

5 It will thus be seen that I have provided a highly novel, simple, and efficient means wherein the blade per se may be extended at various angles with respect to the mount thus permitting of the proper pruning operation.

10 Minor changes may be made in the invention without departing from the spirit or scope of the appended claims.

Having thus described the invention, what 15 I claim as new and desire to secure by Letters Patent is:—

1. In a pruning saw of the class described, a handle, a bracket depending from the forward portion of the handle, a bow secured 20 at its inner end to the forward end of the handle and being of flexible material, a saw blade swivelly connected at its forward end to the free end of the bow, a rod adapted for 25 slidable movement through an opening formed in the depending bracket, the forward end of said rod being connected to the inner end of the saw blade, means for effecting the rotation of said rod and said saw blade when the rod is in one position whereby the blade may be adjusted to any desired 30 angle, said means comprising an elongated wire rod secured at its forward end to the rear end of the aforementioned rod, a manually actuated lever pivotally 35 mounted on the rear end portion of the handle, a bracket, the rear end of the wire rod being slidably secured to the bracket, a link connecting said bracket to the pivoted lever, a handle forming loop arranged in the wire 40 rod to facilitate the turning thereof when the lever is actuated and said wire rod is moved forwardly, and cooperating means between the bracket and the first mentioned rod when the latter is in another position 45 for locking the same against rotation and holding the blade in its adjusted position.

2. In a pruning saw of the class described, a handle, a bracket depending from the forward portion of the handle, a bow secured 50 at its inner end to the forward end of the handle and being of flexible material, a saw blade swivelly connected at its forward end to the free end of the bow, a rod adapted for

55 slidable movement through an opening formed in the depending bracket, the forward end of said rod being connected to the inner end of the saw blade, means for effecting the rotation of said rod and said saw blade when the rod is in one position whereby the blade may be adjusted to any desired 60 angle, means carried by the bracket and cooperating with the rod when the latter is in another position for locking the same and the blade against rotation for holding the blade in its adjusted position, said last mentioned means comprising a block slidably mounted in the opening in said bracket, said block being provided with a non-circular bore, a portion of the rod being non-circular 65 in cross section.

70 3. In a pruning saw of the class described, a handle, a bow secured at one end to the forward end of the handle, a pair of brackets depending from the forward end portion of the handle and provided with registering 75 openings, the opening in the forward most bracket being enlarged, a block adapted for slidable movement in the enlarged opening of the forwardmost bracket, said block being provided with a non-circular bore, a saw 80 blade swivelly connected at its forward end to the free end of the bow, a rod adapted for slidable movement through the block and the opening in the other bracket, the forward portion of said rod being non-circular 85 in cross section, the rear portion of the rod being threaded, means connected to the rear end of the rod, the forward end of said rod being connected to the rear end of the saw blade, means connected with the rear end of the rod for effecting the sliding movement thereof to dispose the threaded portion of the rod within the non-circular bore of the block, additional means for rotating the rod when in such position for adjusting the saw 90 blade to any angle, said non-circular portion of the rod when disposed within the non-circular bore of the block holding the rod against rotation and the blade in its adjusted position, and a nut threaded on the 95 threaded end of the rod and engaging the other bracket for preventing the sliding movement of the rod.

100 In testimony whereof I affix my signature.

AUSTIN ENOS KNESS.
